UNITED STATES PATENT OFFICE.

WALTER WRIGHT, OF SAN FRANCISCO, CALIFORNIA, ASSIGNOR, BY MESNE ASSIGNMENTS, TO UNDERWOOD COMPUTING MACHINE COMPANY, A CORPORATION OF NEW YORK.

COMPUTING ATTACHMENT FOR TYPE-WRITERS.

1,244,397.

Specification of Letters Patent. Patented Oct. 23, 1917.

Application filed March 22, 1909. Serial No. 485,046.

To all whom it may concern:

Be it known that I, WALTER WRIGHT, a citizen of the United States, residing at San Francisco, in the county of San Francisco and State of California, have invented new and useful Improvements in Computing Attachments for Type-Writers, of which the following is a specification.

The present invention relates to computing attachments for typewriters, although it is to be understood that the invention may be embodied in an independent machine.

The object of the invention is to provide an apparatus of this character comprising improved means for simultaneously computing columns of figures vertically and horizontally or securing vertical footings and cross-footings; also one wherein great variability is obtained in the size and arrangement of the various columns so computed; and one in which the intervening space between the different columns may be reduced to the same extent as the variability of the columns. I provide in such an apparatus a plurality of computing mechanisms, either of which may be stationary or movable, each one having an independent operator which may be driven in either direction, or rendered inoperative at will, independently of the other; also means whereby the first column to be computed horizontally may be commenced as close to the left hand margin of the paper as may be desired, whatever be the size of the column; also means whereby the computing mechanism may be disconnected from the typewriter carriage, when desired, so as to avoid the necessity of moving the latter when not computing; also means for preventing the depression of a typewriter key at each fourth type-writing space; also means for preventing the operation of the master wheel or actuator before the typewriter carriage has completed its movement. I also provide two computing means, each having a master wheel or actuator, and means for simultaneously moving the movable elements of the two computing means and for disconnecting either, whereby only one of said elements is then capable of being operated; also, in such an apparatus, a plurality of computing mechanisms, individual actuators therefor, and means for producing intermittent movements of each actuator, relative to its corresponding computing mechanism.

In the accompanying drawings, Figure 1 is a front view of the machine; Fig. 2 is a top plan view thereof; Figs. 3, 4, 5 and 6 are broken enlarged detail front views of the mechanism, in various positions, for connecting the numeral keys with the computing mechanism and for disconnecting them therefrom; Fig. 7 is a broken vertical transverse section of the front portion of the machine, particularly showing the parts illustrated in Figs. 3 to 6; Fig. 8 is a broken plan view of the computing controller; Fig. 9 is a sectional view of the same, showing the parts in a different position; Fig. 10 is a cross section taken in front of the controller; Fig. 11 is a cross section on the line $\alpha-\alpha$ of Fig. 8; Fig. 12 is a perspective view showing the safety connections between the controller and the typewriter escapement; Fig. 12^a is a side view of part of said connections; Fig. 13 is a front view, partly in section through a portion of the computing mechanism; Fig. 14 is a bottom plan view of the same, partly broken away; Fig. 15 is a transverse vertical section of the same; Fig. 16 is a perspective view, on a reduced scale, of one of the washers; Fig. 17 is a perspective view of one of the transfer wheels; Fig. 18 is a similar view of the same on the opposite side to that of Fig. 17; Fig. 19 is a perspective view of one of the computing wheels; Fig. 20 is a view, similar to Fig. 17, of one of the transfer wheels which extends through a partition; Fig. 21 is a broken plan view, partly in section, of the actuator shaft and the tube moving with the actuator; Fig. 22 is a perspective view of the actuator; Fig. 23 is a detail front view showing a partition and parts connected therewith; Fig. 24 is an enlarged detail front view of connections between two computing mechanisms; Fig. 25 is a plan view of the column stop bar; Fig. 26 is a cross section on the line $y-y$ of Fig. 24; Fig. 27 is a similar view on the line $z-z$ of Fig. 24; Fig. 28 is a detail perspective view, showing the mechanism for locking at each fourth writing space; Fig. 29 is an end view showing the driving mechanism; Fig. 30 is a detail front view of a modified form of the invention.

General use.—The drawings show the invention as applied to a "Remington" typewriter, but it is to be understood that, with suitable changes, it may be applied to a type-

writer of any standard construction, and also that the invention may be embodied in the form of a computing machine, or a computing and printing machine, complete in itself, 5 and not attached to a typewriting machine.

Key connection control.—Secured to the frame 1 of the typewriting machine is a vertical plate 2 extending longitudinally of the machine over the key levers 3, (Figs. 1, and 10 3 to 7); and, secured upon the front side of said plate 2, are guides 4 for a slide bar 5. Through holes in said slide bar pass the stems 6 of hooks 7, said hooks being adapted to enter eyes 8 in loops 9 secured around the 15 numeral key levers 10. Said hook stems, in the manner to be presently described, constitute the means for controlling the operation of the computing mechanism. It is sufficient for the present to observe that, 20 when said hooks are in engagement with said eyes, said means are in operative position, so that through the depression of the numeral keys the computing mechanism is actuated, but, when the slide bar is moved to the right, 25 so that the hooks are disengaged from said eyes, the computing mechanism is disconnected from the numeral keys. To move said bar longitudinally, there is secured upon said bar near the left hand end thereof 30 a socket piece 11, into which extends a pin 12 secured upon the lower arm of a lever 13, pivoted at 14 on the plate 2, the upper end of said lever being connected by a link 15 with the lower end of a switch lever 16 pivoted at 17 on said plate 2. Stop pins 18 on 35 the plate 2 limit the rocking movement of the lever 16. Also pivoted at 19 upon said plate is a hand lever 20 connected with a link 21 which, at its other end, is connected to a 40 pin 22 secured in the upper end of a lower arm 23 pivoted upon the lower end of the switch lever 16, said pin also entering a slot 24 in an upper arm 25, secured to a short rock shaft 26, which extends through a sleeve 45 27 in the top of the lever 16 and carries upon its rear end an arm 28 (Fig. 7), to the outer end of which is connected a collar 29 which slides upon a rod 30 connected to a bracket 31 pivoted upon the rear side of the plate 2. 50 Between said bracket 31 and said collar 29 is interposed a spring 32 coiled around said rod.

Shift key control.—In the Remington machine, as is well known, each type bar carries 55 two type, of which one prints normally and the other only when the shift key is depressed. All of the nine digits are arranged in the typewriting machine to correspond to what are known as the "lower case" characters of the top row of keys 33, so that they 60 may be printed by said keys without using the shift key. Since some other character than a numeral is also carried on each numeral type bar, therefore, if the shift key is used, and a numeral key operated, said other

character is then printed. It is therefore desirable at that time to operatively disconnect the computing mechanism from the numeral keys. In the drawings, (see Figs. 2 and 7), 34 indicates the typewriter shift key, 70 which is connected in the usual manner by a link 35 to a bell crank lever 36, serving to shift the platen 37 in the usual manner. To said bell crank lever 36 is rigidly attached an arm 38, which is connected at 39 to a siphon-shaped depressor 40, of which the rear and longer leg 41 slides in a guide 42 secured upon the rear of the plate 2, while the short front leg 43 is adapted to depress the pin 22, when said pin has been moved to its extreme right hand position. 75

The following is the operation: In the normal position of the typewriter, in which it is not desired to use the computing mechanism, the parts are in the position shown in 80 Fig. 3. It will be seen that in this position the slide bar 5 has been moved to the right, and consequently the hooks 7 are disengaged from the eyes 8 and the computing mechanism is disconnected. It will also be seen, 85 upon comparing Figs. 3 and 6, that, if the shift key 34 be operated the short leg 43, when depressed, will not impinge upon the pin 22 or any part of the mechanism, so that the printing mechanism is 90 free to be actuated in precisely the same manner as if the computing mechanism were not attached thereto. When it is desired to bring the computing mechanism into continued use, the hand lever 20 is raised, which 95 has the effect of moving the link 21 to the right, and swinging the lower and upper arms 23, 25 to the right into the position shown in Fig. 5. Consequently the rod 30 also moves to the right, and, when it does 100 so, the rear arm 28, in rocking from its position on the left of the pivot 17 to its position on the right thereof, depresses the upper end of the coiled spring 32, producing an upward pressure by said spring against the collar 29. This upward pressure against said 105 collar 29 produces an upward pressure against the rock shaft 26, and therefore tends to turn the switch lever 16 to the left upon its pivot. The turning of the lever upon its pivot correspondingly turns the lever 13, which moves the slide bar 5 to the left, into the position shown in Fig. 5. The numeral keys are thereby all connected with the computing mechanism, which is 110 now adapted for continuous use.

As is well known, in the Remington and other shift key machines, in which the numeral keys are used for printing other characters besides numerals, it is while the shift 115 key is held depressed that the striking of a numeral key causes the other character to be printed. It is necessary that the computing mechanism be rendered incapable of operation while such other character is being 120 125 130

printed, and therefore while the shift key is thus held depressed; and it is desirable, for convenience and rapidity of operation, that this disconnection should be done automatically, and that the computing mechanism should be automatically connected again upon the release of the shift key. It will be seen that this result is accomplished by the mechanism above described, for, as shown in Figs. 6 and 7, upon the depression of the shift key, the short arm of the depressor 40 which is depressed by the depression of the shift key, has impinged upon the pin 22, and has thereby caused the switch lever 16 to swing upon its pivot 17, and move the slide bar 5 to the right, so as to disconnect the computing mechanism from the numeral keys. The parts are then in the position shown in Fig. 6, in which the pin 22 is on the right of the pivot 17, as are also the guide rod 30 and the coiled spring 32. Hence the spring 32 occupies the same position as when the computing mechanism is connected, and, consequently, when the shift key returns to normal position, and carries with it the depressor 40, raising the same from the pin 22, the spring 32 again acts to move the upper part of the lever 16 to the left, so as to move the slide bar 5 to the left and connect the computing mechanism with the numeral keys. In such a position, since the upper end of the lever 16 is on the right hand side of its pivot 17, and the spring 32 exerts an upward pressure against said upper end by means of the rear arm 28, the effect of the pressure of said spring, when the shift key is released, is to swing the lever 16 from the position shown in Fig. 6 to the position shown in Fig. 5.

Temporary reverse.—It may be desired to temporarily disconnect the computing mechanism from the numeral keys, as when it is desired to print numerals without effecting a computation. For instance, a figure may not have been printed plainly enough, and yet the computing mechanism has been already operated, so that a reprinting of said figure would have the effect of repeating the addition or subtraction. Or, on the other hand, it may be desirable in statistical work to print figures at different points of the writing line of the paper without computing, so that while the computing mechanism should be disconnected for the main portion of the line, but, at certain points on the paper, it might be desired to print figures and also make a computation. In this, or other cases where it is desired to print figures without effecting a computation, a temporary key 46 is used. The stem 47 of said key carries a pin 48 which engages an arm 49 extending from a rock shaft 50, which also carries a short arm 51 connected by a link 52 with the pin 22, which is carried by the end of the arm 28, so that the depression of said key 46 has the effect of drawing down the link 52. But, whether the parts be in the position shown in Fig. 3 or in that shown in Fig. 5, in either case a downward pull upon the pin 22 will have the same ultimate effect. For it swings the lever 16 upon its pivot 17, either from the position shown in Fig. 3 to that shown in Fig. 4, or from the position shown in Fig. 5 to that shown in Fig. 6, the effect in either case being to move the parts into the opposite position to that which they would otherwise occupy but for the depression of said key. This effect is continued so long as the temporary key is depressed. The result is that, if this temporary key should be depressed when the computing mechanism is operatively connected, as shown in Fig. 5, the effect would be to render the computing mechanism inoperative so long as the depression of the temporary key continues, as shown in Fig. 6; permitting figures to be printed without computation; or, if the temporary key should be depressed when the computing mechanism is disconnected, as shown in Fig. 3, the effect would be to temporarily connect the computing mechanism, as shown in Fig. 4, and to maintain it connected, so long as the temporary key is depressed, so that the printing of a figure will correspondingly effect a computation.

Controller.—The stems 6 are connected at their upper ends to bell crank levers 55 pivoted on the plate 2, (Fig. 8) the other arms of which are connected to rods 56, passing within a ring 57 secured to a bracket 74 connected to the plate 2, said rods being connected respectively to blocks 58 connected to levers 59 pivoted on said ring 57. Thus, upon depressing any one of the numeral keys, the outer end of the corresponding lever 59 is moved to the right. Secured on the right hand side of the frame of the typewriting machine is a bracket 60, (Fig. 1) supporting a vertical plate 61, carrying posts 62, supporting a guide plate 63, having a circular series of holes, through which extend the ends of nine pusher rods 64, pivotally attached to the several bell crank levers. Said plate 63 is additionally supported by a strut 73 connected to the bracket 74 attached to the plate 2. Having its bearing in the plate 61 is a shaft 65 of a controller or primary escapement wheel 66, which, as will be presently described, is under constant rotational pressure. Stop bolts or escapement teeth 67, of which there should be not less than ten, though twelve are preferably illustrated, slide in a circular series of slideways 68 in said controller which slideways register with the pusher rods 64, and said bolts project to the left of said controller normally, and until they are displaced by the action of the pusher rods 64. An annular coiled spring 69, which surrounds the controller in a

groove therein deep enough to intersect the slideways for the bolts, and which is adapted to engage one or the other of two grooves 70 (Fig. 9) formed in each bolt, yieldingly 5 maintains the bolts in the positions to which they have been moved. When any numeral key has been operated, and the corresponding pusher rod moved through the guide plate, its end impinges upon the end of one 10 of the stop bolts projecting from the left hand side of the controller, and moves said stop bolt to the right, so that its other end then projects from the right hand side of said controller. The operation of a numeral 15 key not only thus projects a bolt, but actuates an escapement, hereinafter described, for the controller, so that the controller is released and rotates. Its stoppage, after a certain extent of rotation, is effected by 20 means of the then projected stop bolt impinging against a rotary stop wheel or pinion 71, (Figs. 8, 9, 10) and the extent of rotation depends upon its circumferential distance from the stop wheel, when it was 25 so projected, and therefore upon the particular pusher rod and the particular key lever which were then operated. Upon the next operation of a numeral key and rotation of the controller, the stop bolt is, by 30 means of a cam wedge 72 on the plate and located in the path of the projected stop bolt, returned to its normal position, in which it projects from said controller to the left instead of to the right, and it is 35 retained in that position by the annular coiled spring.

Escapement.—Secured upon the front side of said plate 2 is a guideway 75 for a stem 76, the other end of which is pivotally connected to a lever 77 pivoted at 78 upon the ring 57, to the other arm of which lever 77 is secured a spring 79, which normally tends to draw said arm to the left, and therefore said stem to the right. Said 40 stem 76 carries a disk 80, and all of the rods 56 pass through holes in said disk. When any numeral key has been operated, and thereby the corresponding rod 56 moved to the left, the block 58, by which it 45 is connected to the bell crank lever 59, then abuts against said disk 80, and carries said disk with it to the left, thus rocking the lever 77. The long arm of said lever is connected at its extreme end by a link 81, 50 with an arm 82 on an escapement controlling rock-shaft 83, so that, by said movement of said lever, said escapement shaft is rocked. Said escapement shaft carries, adjustably two disks 84, 85, (Fig. 12) spaced 55 apart a short distance, and having respectively formed in their beveled edges notches or recesses 86, 87, offset from each other. Through said plate 61 passes a stop shaft 88, which, on the left side of said plate 61, 60 carries the before-mentioned stop wheel or

pinion 71, which is star-shaped, having points any of which is adapted to lie in the path of a bolt in the controller which has been projected to the right, and arrest said controller if said stop shaft is at that time 70 itself held fast and non-rotatable. Secured upon the end of said stop shaft, upon the right hand side of the plate 61, is a secondary escapement wheel 89, having the same number of points as the wheel 71, a point 75 of which escapement wheel normally abuts against the first or rear disk or dog 84. Therefore, when any numeral key has been actuated, and thereby the escapement shaft 83 rocked, the disk 84 is thereby moved 80 until the notch 86 therein comes opposite to the point of the escapement wheel 89, which can then immediately pass through said notch. This it immediately does, because, as already mentioned, the controller 85 shaft is under constant rotational pressure, so that the previously projected bolt is pressing against a point of the rotary stop wheel 71. After said point has passed through said notch 86, it then abuts against 90 the second disk 85, and the stop shaft is again held from further rotation. The slight movement thus given to the stop wheel 71 allows the bolt or tooth 67 arrested thereby to move only a very short 95 distance. Then, upon the release of the numeral key, the escapement shaft 83 returns to its original position, in which position the notch 87 in the second disk 85 now comes opposite to the said beveled point or 100 arm of the escapement wheel 89, which thereupon escapes therethrough, under the pressure of the projected stop bolt against an arm of the rotary stop wheel 71. This 105 pressure rotates the shaft 88 so that the next succeeding arm of the rotary stop wheel is brought into the path of the last projected bolt, which then impinges against said latter arm, thus again producing rotational pressure on the stop shaft, rotating 110 said shaft until the next succeeding point of the escapement wheel 89 is brought up against the first escapement disk 84, and the parts are then again in their normal position, ready for another operation. It will 115 thus be seen that the extent of movement of the controller shaft is dependent upon the angular position, relatively to the rotary stop wheel 71, of the pusher rod actuated, and therefore upon the particular numeral 120 key which is operated.

Driving.—It has been already mentioned that the controller shaft 65 is under constant rotational pressure, tending to rotate said shaft whenever released by the escapement. This rotation is derived from any suitable motor, an electric motor 92 being shown herein. The shaft 93 of said motor has secured thereon a head 94 to which are secured, by screws 95, the ends of three spring 130

- arms 96 (Figs. 8, 29). To the other ends of said arms are secured arcuate shoes 97, which bear against a fiber lining 98 of a cup-shaped head 99 secured upon a shaft 100 having a bearing in a bracket 101 secured to the plate 61.
- Said shaft 100 has secured thereon a bevel gear 102 which meshes with a bevel gear 103 on a shaft 104 rotating in a bracket 105 secured to the inner side of the plate 61, as shown in dotted lines in Fig. 29, and carries on its outer end a gear wheel 106 which meshes with an idle wheel 107, which in turn meshes with a gear wheel 108 upon the controller shaft 65. It is by this means that the controller shaft is given a constant rotational pressure always in the same direction, rotating the shaft whenever it is released.
- 20 In order to vary the amount of friction transmitted from the rotating shaft, the outer end of the motor shaft 93 is threaded, and upon said threaded end is screwed a flanged sleeve 109 which is adapted to bear 25 against the spring arms 96. By screwing said sleeve in or out, the pressure upon said spring arms, and therefore the pressure of the shoes 97 against the lining 98 of the head, is increased or diminished as desired.
- 30 *Computing mechanism.*—The frame of the computing mechanism comprises end plates 110, 111, and a series of transverse partitions 112. These partitions are connected by an upper bar 113 and two lower bars 35 114, 115, and are spaced from each other by sleeves 116, around the bars. Said bars at one end, after passing through the end plate 110 into the plate 61, are secured by means of screws 117 (Fig. 13). Upon the 40 other ends of said bars, where they pass through the end plate 111, are screwed nuts 118, washers 119 being interposed between said nuts and the end plate 111.
- Each sleeve 116 is of such length that 45 said sleeve and a partition occupy a longitudinal distance equal to that of four typewriting spaces. Between two adjacent partitions are interposed three register wheels 120, each of the width of one typewriting 50 space, and two spacing washers 121, 122, next to the respective partitions, which washers and a partition together occupy a distance equal to one typewriting space. Said register wheels 120 are in the form of 55 rings supported upon a hollow shaft 123 of comparatively large diameter, supported by the partitions and end plates. Each register wheel has formed on one side thereof a thin gear wheel 124, by means of which 60 it is rotated in the manner to be presently described. On each side of the middle register wheel is a thin washer 125, shown in detail in Fig. 16, having an upper circular opening 126 which surrounds the hollow 65 shaft 123, thereby supporting the washer

on said shaft, having also a lower circular hole 127 and a foot 128 contained between the sleeves 116.

In oblique slots in the front edges of partitions and end plates is a shelf 129. Also 70 extending through all the partitions is a carrying wheel shaft 130, having thereon a series of carrying wheels 131, each formed with gear teeth 132. Supported on one side by said gear teeth 132 and on the other 75 side by the shelf 129, (Fig. 15) are a series of computing wheels 133, each computing wheel being of a thickness equal to one typewriting space. Secured in the partitions are short spacing cylinders 134 of a thickness equal to one typewriting space, and 80 co-axial with the computing wheels.

Each computing wheel 133, shown in detail in Fig. 19, is formed on one side with gear teeth 135, adapted to mesh with the 85 gear teeth 124 of the corresponding register wheel, and is also formed, next to, said gear teeth 135, with an annular shoulder 136, upon which is a single carrying tooth 137 forming a lateral extension of one of 90 the gear teeth 135. Each computing wheel 133 is also formed with a reduced hub portion 138, (Fig. 19) which, of the left hand one of the computing wheels of a group of three, rotates within the spacing cylinder 95 134 contained within and secured to the partition on its left.

Through said computing wheels passes a longitudinal computing shaft 140, rotated in a manner to be presently described, and upon which shaft can slide a sleeve 141. The shaft 140 is preferably square, and the sleeve has a corresponding square opening fitting snugly on the shaft, so that said sleeve always rotates with the shaft. Said sleeve 100 (Fig. 22) at its advancing end 139 is rounded or tapering, and at the rear end is formed with an annular groove 142, and in said groove are pins 143 projecting inwardly 105 from the end of a non-rotatable tube 144 which can telescope around said square shaft out of contact therewith. Said sleeve 141, is formed with actuating pins 145 which are adapted to engage one or the other of ten recesses 146 formed by internal gear teeth 110 147 within the computing wheels. As will be presently described, the tube 144, and therefore also the sleeve 141, travel within the said computing wheels through a distance of one typewriting space with each 115 step movement of the typewriter carriage, and in the positions of rest is either at the middle of a computing wheel or at the middle of a spacing cylinder 134 between two 120 groups of computing wheels. By the rotary 125 movement of the square shaft, to be presently described, the actuating pins 145 are always rotated through an exact multiple of one tenth of a revolution, so that, after 130 making a rotation within any one comput-

- ing wheel and thereby causing the computing wheel to rotate with them they are in position on the next advance to be moved longitudinally and exactly mesh with some one pair of opposite recesses of the next computing wheel. The rotation thus imparted to the computing wheel causes the register wheel to rotate through a corresponding angular distance.
10. *Transfer mechanism.*—Each time that the computing wheel makes a complete revolution, the single carrying tooth 137 formed thereon engages one of five lugs 150 of a carrying wheel 131 loose upon said shaft 154, the gear teeth 132 of which mesh with the external gear teeth 135 on the right hand side of the next computing wheel 133 on the left, and said wheel 133 on the left is thereby partly rotated through one-tenth of a revolution. Said carrying wheel is also formed with a disk-like portion 151 having five concavities 152 each in an arc of a circle of slightly greater diameter than that of a transfer cylinder 153, preferably of rubber or other resilient material, secured to a shaft 154 and rotated herewith, which shaft, as hereinafter described, constantly rotates. Said shaft 154 is supported in bearings at suitable intervals in the partitions and end plates, or if desired, may be carried only at the ends. When, by the advance of the single carrying tooth 137 in the manner just explained, the carrying wheel has been moved through an angular distance corresponding to a part of one-tenth of the revolution of the computing wheel, it is then in such a position that one of its projecting portions 153, between two adjacent concavities 152, has been forced into sufficiently close contact with the constantly rotating transfer cylinder 153, and is rotated with the latter until its next concave side 152, in turn, assumes a position over the rubber body 153 of the transfer shaft 154.
15. The hub of each third carrying wheel is of a sufficient length, as shown at 148 in Fig. 20, to extend through a partition being permanently supported therein to carry from the computing wheel on the right hand side of the partition to the next computing wheel on the left thereof (see Fig. 14). Suitable spacing washers 149 are provided to maintain such carrying wheel in its proper relation to the other wheels. The spacing cylinders 131 are cut away, as shown at 223 to permit the carrying wheels 131 opposite thereto to freely rotate.
20. In order to align the figures on the register wheels, and to insure that the carrying wheels 131 are not unduly rotated, there is provided, for each such carrying wheel, a pivoted arm 156 carrying a roller 157 which is pressed by a spring 158 into one of the concave sides 152 of said carrying wheel. It will thus be seen that each computing
- wheel cannot be advanced by the transfer mechanism more than one-tenth of a detent revolution, first, because of the roller 157, and, second, because of the form in the peripheries of the carrying wheels, the points 70 of which cannot take hold of the rubber body of the transfer shaft and rotate with it, unless positively forced thereinto. It will be seen that all of the computing devices contained in the main computing mechanism 75 are operatively connected throughout the entire series, so that the whole series can be used for a single column or for a variable number of independent columns.
- The entire mechanism is covered by a casting 159 having a slot 219 through which a line of figures on the register wheels is exposed to view.
25. *Independent denominational computation.*—The above construction and arrangement of computing wheels, carrying wheels, and transfer shaft constitute what is believed to be a novel form of computing mechanism for machines, such as adding machines, in which a rotary impulse is imparted directly to a series of devices in succession, corresponding to the several denominational values of the computing mechanism.
30. In a mere registering mechanism, such as 95 a cyclometer, in which the direct rotary movement is always imparted to the terminal member of the group of computing devices, and the other devices of the group are merely for the purpose of accumulating the 100 movements thus imparted, it is possible, for all of said devices to be connected for carrying by a continuous train of gearing.
35. But in mechanisms like the present, in which it is necessary to add directly, not 105 only units, but also tens, hundreds, and so on, such a continuous train of gearing is admissible. For instance, suppose it were attempted to compute with devices so connected, and the "tens" device stood at 9, 110 and then an addition were made to the device corresponding to the "hundreds" column, the effect would be to rotate, not only the said device, but also the device of the "tens" column. The reason for this is 115 that, when the "tens" wheel stands at 9, its "carrying" tooth is necessarily in contact with the teeth, or similar devices, of the "hundreds" wheel or of the carrying wheel therefor, and, if the wheels are connected in 120 a continuous train, any motion of the latter will therefore produce a corresponding motion of the former. With the present construction this difficulty is avoided in the following manner.
40. It should first be remembered that each computing wheel is positively geared with its carrying wheel on the right, that is, the carrying wheel which connects it with the next computing wheel on the right, but its 125

only connection with its carrying wheel on the left, which carries to the next computing wheel on the left, is through its carrying tooth. Therefore, each time that a computing wheel is rotated, its carrying wheel on the right, geared thereto, will also be rotated, but the latter wheel will not rotate the next computing wheel on the right, even though said next computing wheel on the right be standing with its carrying tooth at the position corresponding to the display of the figure "9" in addition, or "0" in subtraction. For, when a computing wheel stands in this position, the five lugs 150 on the carrying wheel on the left can freely rotate without coming in contact with the carrying tooth 137. Consequently, there is no rotation transmitted from a computing wheel on the left to a computing wheel on the right through the carrying wheel.

Since, however, the carrying tooth 137 of a computing wheel, when either "at 9," or "at 0," is in such a position that the five lugs 150 on the carrying wheel do not engage the same when said carrying wheel rotates in either direction, it is evident that said computing wheel has considerable lost motion, in moving from "9" to "0" or "0" to "9," before it can be brought into operative engagement with the five lugs 150 of the carrying wheel to the left, and it would therefore be impracticable to transmit, through said carrying wheel, to the computing wheel on the left, an amount of rotation, namely, one-tenth of a revolution, equal to that transmitted to said carrying wheel from the computing wheel operated, since the first part of this rotation is made without producing any motion of the said carrying wheel. It is to overcome this difficulty that the transfer shaft is used, for thereby, although the latter part of the motion of one-tenth of a revolution of the computing wheel, after it comes in through operative engagement with the carrying wheel on the left, is effective in imparting only a partial rotation to said carrying wheel, yet this is sufficient, for it is sufficient to cause a projection 155 of the carrying wheel to engage the rubber cylinder 153 of the transfer shaft, and since the latter is in constant rotation, the transfer shaft completes the work which was omitted by the computing wheel in the first part of its rotation, and moves the carrying wheel through the remainder of the necessary rotation to rotate the computing wheel on the left through one-tenth of a revolution.

The principle, then, embodied in this mechanism is, first, to permit the computing wheel to stand in such a position, when at "9" or "0," that the carrying wheel on the left can be freely rotated in either direction, and, second, because this arrangement necessarily requires lost motion of the computing

wheel on the right, to compensate for this lost motion by providing extraneous means for rotating the carrying wheel through the latter part of its movement. This carrying wheel rotating means may, however, be used with many other kinds of tens-carrying mechanisms, particularly where it is desired to take up lost motion.

Duplicate computation.—The machine, as shown provides for two independent computing mechanisms, the secondary computing mechanism and its operating means being hereinafter more fully described. Such parts thereof as it is necessary to refer to will be designated by the affix "x" affixed to the numeral of the corresponding part of the main mechanism.

Addition and subtraction.—The computing shafts 140, 140^x, have respectively secured upon the ends projecting through the plate 61 bevel gears 160, 160^x, which are adapted to be driven by a vertical shaft 161, having at the lower end a bevel gear 162, driven by a bevel gear 163 upon a horizontal shaft 164 having a bevel gear 165 driven by a bevel gear 166 upon the controller shaft 65. When said controller shaft has been released by the depression of a numeral key and rotates through an angular distance corresponding to the numeral key depressed, said rotation is transmitted to the vertical shaft 161 and thence to the shafts 140, 140^x, selectively, in one or the other direction by means of sliding clutches 167, 167^x, slidably upon said vertical shaft 161 but rotating therewith. By means of a lever 168 the clutch 167 is adapted to be brought into operative engagement with either of two bevel gears 169, 170, loose on the shaft 65 and always in engagement with the bevel gear 160. If said lever 168 is moved upward, then the clutch 167 is moved into engagement with a clutch member 171 formed within the upper bevel gear 169, thereby rotating the computing shaft 140 in the direction proper for addition. If said lever is moved downward, the clutch 167 engages the clutch member 172 of the lower bevel gear 170 and rotates the shaft 140 oppositely to its former direction, causing the computing wheels to subtract. If said lever is moved to a mediate position, the clutch 167 is out of engagement, and the computing shaft 140 does not rotate. In order to retain the lever 168 in any position to which it has been moved, there is provided a pivoted bar 173, secured to the front wall 174 of a casing 175 around the end gearing, said bar having three notches 176 adapted to selectively receive the edge of the lever 168, and the bar being pressed against said lever by a spring 177.

167^x, 168^x, 169^x, 173^x, indicate parts for the secondary mechanism corresponding to the parts 167, 168, 169, 173, of the main mechanism.

The transfer shaft 154 has a constant rotary movement which is derived from the electric motor 92 by means of a gear wheel 180 on the shaft 93 of the motor, meshing with an idle gear wheel 181, which in turn meshes with a gear wheel 182 on a shaft 164', carrying a bevel gear 163' which meshes with a bevel gear 162' on a vertical shaft 161', with which coöperate parts similar in their general construction and arrangement to those immediately coöperating with the vertical shaft 161, except as to the form of the clutch sleeve 167', which, in this case, has only a pair of teeth 182' instead of a number thereof, on each side, the reason being that said shaft 161' revolves constantly at a rapid speed, and, when the direction of computation is changed, this must be done while said shaft 161' is in motion, whereas the direction of motion of the computing shaft 140 is never changed except when the shaft 161 is at rest. By arranging that the clutches 167, 167', for the computing shaft and for the transfer shaft are actuated by a common lever 168, it is insured that the transfer shaft will always be rotated in unison with the computing shaft.

Grouping.—The figure wheels are visibly spaced into groups of three, each group, together with the spacing means, occupying four writing spaces of the typewriter. The spacing is preferably effected by the partitions, one of which is interposed between each group and the next, as shown in Figs. 13, 14, and occupies the fourth writing space, or a portion thereof. If it occupies less than a full fourth writing space, the three figure wheels which occupy the remainder of the four writing spaces of the group should be made correspondingly wider, but always so that the sum of the widths of the three figure wheels, together with that of the spacing means, is equal to four writing spaces of the typewriter.

The computing wheels are also divided into groups of three by the partitions, and the hub 138 of the computing wheel at the left of the group rotates in the spacing cylinder 134, which is of sufficient internal diameter to permit the actuating pins 145 to rotate freely therein. Hence said pins have no effect on the computing mechanism, in case the computing shaft should be rotated at the time the actuating pins are at any such fourth space in the computing mechanism. This arrangement provides that, without disconnecting the numeral key levers from the computing mechanism, the machine is free to operate at each fourth writing space without affecting the computing wheels, so that this space can be used for pointing off the hundreds from the thousands, the thousands from the millions, and so on, and for separating different columns, thereby avoiding any derangement of the computing mecha-

nism, or error in the computation, through erroneously striking a numeral key at that point.

In order to ascertain at any desired time the points at which computation is taking place, either in the vertical or in the horizontal computing mechanism, there are provided movable pointers 185 which are each in vertical alinement with the actuator pins of the corresponding computing mechanism.

Horizontal computing mechanism.—The secondary mechanism is similar to that of the main in the relation of the computing wheels to the figure wheels, in the general construction of the transfer shaft, and in the clutch mechanism for shifting both the computing and transfer mechanisms into any one of three positions, to add, to subtract, or for throwing out of operation. The description, therefore, of such parts of the main computing mechanism as are also found in the horizontal computing mechanism applies also thereto, corresponding parts being indicated by the affix "x" for the horizontal computing mechanism.

One object of the horizontal computing mechanism is to furnish a cross computation of a row of figures whether added to, or subtracted from, the several columns which are being computed by the main computing mechanism, as said figures are progressively written in said columns. This mechanism is also adaptable for a billing machine, that is, a machine by which there is obtained a balance of one or more columns in which some items are to be subtracted, as well as others added, the machine being provided with means for obtaining a horizontal computation of two or more rows, or a balance or difference of two numbers in a row, to write the total or difference in a separate column, and at the same time to reset the horizontal computing mechanism in readiness for a similar operation, while still retaining the result of each such independent operation in a separate column, the vertical computation of which is retained in the main computing mechanism.

Resetting and error correction.—The means for reversing the direction of rotation of the actuator pins or master wheel 145 provides a convenient means for resetting to zero. This means may be of use either to correct the computation of a figure erroneously printed, or to clear a series of figure wheels to zero to begin a fresh computation. If, just before writing the result of any computation either vertical or horizontal of a series of numerals, the corresponding computing mechanism be reversed, then, at the time of so writing said result, the figure wheels of that mechanism will be automatically set to zero, ready for the next computation.

The writing of the result of the cross-com-

putation in this manner would bring the figure wheels of the horizontal mechanism to zero, at the same time adding it in a grand total column of the mechanism. The writing of the result of the vertical computation brings the figure wheels of the vertical computing mechanism to zero. The writing of the total of the grand total column has the same effect upon both the vertical and the horizontal computing mechanisms, and this result proves the accuracy of all the totals or balances in the vertical columns, in the horizontal rows, and in the grand total column. The above result is all accomplished in one continuous writing of the figures across the sheet in their respective columns, in the same way as matter is written in the ordinary manner by the typewriter when used for correspondence, the only other manipulation necessary being that of reversing the respective computing mechanism before writing any computation of a row or column.

The arrangement of reversing mechanism, both, for the horizontal and vertical computing mechanisms, affords means for obtaining great variability in the character of the computations that may be effected thereby. For instance, there may be debit columns as well as credit columns, or each individual column, or certain of the columns may contain debits as well as credits, which could be written and computed without any explanation except the use of different colors, by a machine using a parti-colored ribbon as, for instance, black for the debits and red for the credits.

In writing such figures in the several columns, representing the debits or credits as the case may be, the proper computations of such figures are simultaneously effected in the vertical and horizontal computing mechanisms as the figures themselves are written horizontally across the sheet in the various columns.

Vertical actuator advance.—Upon the rear side of the typewriter carriage is secured by arms 190 a rack 191 (Figs. 2 and 12) which meshes with a pinion 192 upon a vertical shaft 193, suitably supported in the frame of the machine, on the lower end of which is secured a bevel gear 194 which meshes with a bevel gear 195 on a shaft 196 extending from the rear to the front of the machine, also suitably supported on the frame of the machine. On the front end of said shaft 196 is secured a pinion 197 (Figs. 1, 2, 25) which meshes with a rack 198 which is secured to a frame 199 which has a sleeve 200 having a slot 201 which receives a feather 202 on a longitudinal rod 203 within said sleeve, said sleeve being thus guided on said rod. Said rod 203 is supported upon the frame of the typewriter at one end by the plate 61 and at the other end

by a bracket 205 secured to said frame. From the above construction it will be seen that said frame 199 moves with the typewriter carriage in a step by step movement but in the opposite direction thereto. To an extension 206 of said movable frame is secured the outer end of the tube 144 which moves the actuating pins 145, and into which the computing shaft 140 telescopes.

Horizontal actuator advance.—The tube 144* which advances the actuating pins 145* for the horizontal mechanism is connected to a cross piece 212, which is moved by a shifter arm 213, pivoted thereto and is secured to a sleeve 214 which slides upon a rod 215 secured to the plate 61, and also to a plate 216 supported on the frame of the machine. Said tube 144* slides upon a fixed round shaft 217 secured at its left hand end in the plate 216, and in the right hand end of said shaft 217 rotates the end of the square computing shaft 140*. Secured to said upper sleeve 214 is a pointer 218 which moves over the display opening 219 in the casing 159 for the register wheels, and points to the register wheel which is in operative position. Secured to said cross piece 212 is a cord 220 which is wound around a barrel 221 actuated by a spring 222, said spring tending to draw said movable frame always to the left.

Column stops.—Secured on said frame 199 is a column stop bar 207 having formed therein a series of sockets 208. In any one of said sockets 208 can be secured by means of a screw 209 a column stop 210 having a projection 211 which, in the operative position of said column stop, projects downward, but, when the column stop is arranged so that the projection extends upward, said column stop is thereby rendered inoperative. The shifter arm 213 carries a shifter 224, having in its upper edge a notch 225, which is adapted to engage any of the projections 211 upon the column stops 210. Said shifter is normally pressed toward the column stop bar 207, by means of a spring 227, so that said notch 225 engages a projection 211 when it has arrived opposite thereto. When the notch 225 is so engaged by a projection, and the actuator frame of the vertical mechanism is moved to the right by the movement of the typewriter carriage to the left, the actuator frame of the horizontal mechanism is also moved to the right in unison with the movement of that of the vertical mechanism.

Actuator return.—Secured upon a stationary support 228 upon the frame of the machine is a short arm 229, upon the end of which is mounted a roller 230, and when the shifter arrives at said roller, the latter rides upon the sloping advancing edge 231 of said shifter and thereby depresses the shifter and its arm 213, which carries the

130

same, against the action of said spring 227, releasing the notch 225 from the projection 211 on the column stop. When it is released, it is immediately retracted by the 5 spring 222, which moves it to the left until the rear sloping edge 232 of the shifter impinges against the projection 211 of the next column stop to the left, which in its turn has been advanced into a position to engage 10 said notch. On the rear side of the notch there is formed a low shoulder 233, the object of which is to prevent any recoil of the shifter when the shoulder 234 on the right of the notch strikes said projection, 15 and also to lock the shifter in a position in which the projection 211 engages the notch 225, the spring 227 maintaining said projection and notch in engagement.

It will thus be seen that the actuating 20 pins 145^x of the horizontal mechanism receive an intermittent advance in unison with the actuating pins of the vertical mechanism, the end of such advance being determined by the position of the roller 230, 25 which position is such that the actuating pins always cease to advance when they have passed through the last of the computing wheels of the horizontal mechanism. A fixed cam 232^a engages the sloping edge 232 30 to disengage the shifter or hook 224 from the pins 211 during the return of the paper carriage to begin a new line of writing.

Variable advance.—The beginning of the advance of the actuator pins 145^x is variably 35 determined by the position of the column stops 210, which can be adjustably secured in the sockets in the column stop bar. This permits the cross-adding of columns located at different parts of the written page, considered widthwise. In said stop bar there is here shown a socket 208 at each fourth writing space, so that, wherever the column stops are placed, the master wheel or actuator pins of the horizontal mechanism are 40 arrested at a point between two groups of computing wheels and commence the next advance from such point. Sockets 208^a may also be provided in the column stop bar at each writing space as shown in 45 Fig. 1. This is of advantage, when it is desired to use the horizontal mechanism by itself and independently of the vertical mechanism, as it permits the column to be placed exactly where desired on the work sheet. It will readily be seen that the horizontal mechanism, while so called, is also 50 equally well adapted for computing vertical columns and thus may be used for billing or other purposes.

60 When it is desired to use the vertical mechanism without producing any movement of the parts of the horizontal mechanism, a lever 236 is moved to the right, said lever having a pin 237 which bears down 65 upon the upper edge of the pivoted arm

213, thereby depressing the shifter 224 so that its notch 225 cannot engage any one of the projections 211 of the column stops, and the column stop bar can reciprocate without said column stops producing any 70 effect upon the horizontal computing mechanism. As indicated at Fig. 21, the silencing lever is held facewise against the wall by the head of the stud on which the lever pivots, so that said lever will stay where 75 it is placed, so that the machine may be set for the performance of vertical addition only, as aforesaid.

Variability of first column.—When the frame 199 of the actuator pins 145 returns 80 to the left with the movement of the typewriter carriage to the right for the purpose of beginning a new line of writing, a special stop 240 on the column stop bar impinges against a pin 241 secured upon the 85 right hand end of a rack 242 which slides in a guideway 243, said rack engaging the upper side of a pinion 244, the lower side of which is engaged by a lower rack 245, which rack slides in a guideway 246, and 90 therefore moves to the right as the said frame moves to the left. A spring 247 around the shaft of the pinion 244, normally moves the rack 245 to the left, and the rack 242 to the right. The rack 245 has a shoulder or extension 248 which, when it is moved to the right, engages a pin 249 extending from the shifter 224, and therefore moves to the right with said rack the arm 213 and the horizontal actuator pins 145^x through 100 the full distance of their travel to the right, and until the sloping advancing edge 231 of the shifter 224 is engaged by the roller 230, which thereupon depresses said shifter and detaches the pin 249 thereon from the shoulder 248 on the rack and releases the shifter therefrom, so that the arm 213 returns to the left under the action of the barrel spring 222. On its return it is arrested by the projection 211 on the first of the series of 110 column stops engaging the notch 225 in said shifter. When the frame 199 re-commences its movement to the right the upper rack 242 follows its movement under the tension of the spring 247, until it reaches its normal 115 position.

The object of the above arrangement is to permit a column of any width, from three to twelve figures, commenced at the first writing space of the typewriter to be computed in the horizontal mechanism along with other columns of the same or greater or less width. Were this mechanism not provided, that result could not be obtained, for, although it would be possible to write 120 a column, say, of three figures wide, at the extreme left of the writing space, and to actuate the first group of three wheels of the horizontal computing mechanism in correspondence with the writing of the figures 130

of said column, yet said wheels so actuated, would not be the proper wheels to be computed with other columns of greater width. For instance, hundreds, tens, and units 5 might be added, respectively, to hundreds of thousands, tens of thousands and thousands. By the above contrivance it is provided that, when a column of three figures or less is to be computed at the extreme left 10 of the writing line, it is only the computing wheels on the extreme right of the horizontal computing mechanism that are actuated. If a column six figures wide is written, then the six wheels on the extreme right 15 of the horizontal computing mechanism are actuated, and so on, thus assuring that, in all cases the computing wheels of the horizontal mechanism will correspond in denominational value to the several figures of the 20 columns.

The commencement of the computation of such first column is controlled by the position of the first column stop, to which the shifter returns at the end of its first movement 25 when released from the rack upon the return of the typewriter carriage. The actuator of the horizontal mechanism then advances with the writing of the figures until the end of the horizontal mechanism is 30 again reached, when the shifter is again tripped, and returns, and is arrested by the next column stop, the position of which, in its turn, determines the number of figures that may be written in the next column.

35 250 indicates a limit stop which arrests the movement of the horizontal actuator frame to the left when it would not otherwise be arrested by a column stop.

In Fig. 30 I show a modification of the 40 invention in which the horizontal mechanism is duplicated, the vertical mechanism being omitted, although it is understood that the vertical mechanism can also be used if desired. This arrangement is very advantageous for billing purposes. For instance, the items of the bill may be set down in a 45 column and computed by one of the mechanisms, say the upper, the lower one being at that time inoperative. When the lower 50 mechanism is set for "addition", and the upper mechanism is set for "subtraction", and the total is written down in another column, to the right or left of the first column, the upper mechanism is thereby reset to zero, while the total is retained in the 55 lower mechanism. This operation may be repeated a number of times and the grand total obtained by the lower mechanism. Then, after so obtaining the grand total, the 60 lower mechanism may be set for "subtraction" and the grand total written down in a third column, thus resetting the lower mechanism to zero. Or, instead of pursuing the above method, a discount may be 65 taken, or any amount deducted, from any

one or more of the totals, the lower mechanism being at that time and for that purpose set for "subtraction", and by setting the lower mechanism to the inoperative position the balance may be placed in the third same 70 or another column and at the same time retained in the lower mechanism.

It will readily be seen that either of said mechanisms can be operated, either for addition or for subtraction, the other being inoperative, or the two mechanisms can both be used for addition or for subtraction, or either for addition and the other for subtraction.

When it is desired to increase the number 80 of such columns and the successive operations, three or more such horizontal mechanisms can be used in the same manner.

Another method in which the construction shown in Fig. 30 can be used is that, the 85 cross computation of each row of a large number of columns on the sheet, can be computed in one of the mechanisms, say the upper, and, as written, the computation can be transferred therefrom to the lower mechanism, at the same time resetting the upper mechanism to zero, the cross computations of such rows being retained and computed in the lower mechanism until the computation is complete.

Speed controls.—By means of the escapement I provide two safety controls.

It is to be remembered that, at the time a numeral key is depressed, the actuating pins 145 are not within the computing wheel 145 which is to be rotated by the next depression of said numeral key, but are still within the computing wheel last rotated, or in a position to have been rotated, and that, before the computation to be effected by the 100 depression of a numeral key takes place, it is necessary that the actuating pins be first brought into engagement with the computing wheel by which the desired computation is to be effected. If the rotary motion of 105 the actuator pins were to commence before the said pins left the one computing wheel and entered the next, evidently confusion and incorrect computation would result. The object, therefore, of the first safety control is to prevent any rotation of the 110 computing shaft before the typewriter carriage, which is the means of bringing said actuating pins into proper position, has completed its movement.

115 It is also evident that if a second numeral key were struck while the computing shaft and controller were still rotating, the proper stop bolt 67 in the controller might not be arrested by the stop wheel 71, and the computation would be rendered erroneous or the mechanism rendered inoperative. I therefore provide the following safety controls:

120 The escapement shaft 83 containing the disks 84, 85, is slidable longitudinally, and 130

is pressed in a longitudinal direction by a spring 252, Fig. 29. This spring operates to move the shaft forward longitudinally only in the intermediate position of the escapement wheel 89, when neither one of its points is engaging a disk on said shaft. As soon as a point of said escapement 89 passes through the notch 87 in the second disk, then the spring 252 acts to move the shaft 83 longitudinally, and it remains in this latter position for a time, which, however, is very minute, until the next point of the escapement wheel 89 strikes the first disk 84 on said shaft 83, and therefore again moves said shaft longitudinally against the pressure of said spring 252. To said shaft 83 is secured a plate 253, which in fact, forms an extension of the arm 82 to which is attached the link 81. When the escapement shaft 83 is rocked so as to permit the point of the escapement wheel which was in engagement with the second disk to pass through the notch therein, said plate 253 has, by the rocking of said shaft 83, been moved downward, and, as soon as said point passes through said notch 87, in the rear disk, the spring 252 moves the shaft 83 longitudinally into such a position that the upper edge of said plate 253 lies underneath a fixed pin 254 projecting from a bracket 255. The computation is completed when the next point of the escapement wheel arrives at the first disk 84 on the escapement shaft, and, if another numeral key be struck before the computation is completed, said key cannot be depressed, for the reason that the depression of said key can only be effected by rocking said escapement shaft 83 by means of the link 81, which cannot be done, because the plate 253 is still immediately beneath the pin 254, and therefore cannot be raised. But, as soon as said next point of the escapement wheel 89 impinges against the first disk of the escapement disk of the escapement shaft, then the pressure of said wheel 89 on said shaft 83, overcomes the pressure of the spring 252 and moves the shaft 83 against said spring, so that the edge of the plate 253 is now moved in a parallel direction from underneath the pin 254 so that said plate is free to move upward and the shaft 83 is free to rock and the numeral key can be depressed.

This speed control is not necessary for any ordinary usage of the machine, and is only included to make it absolutely impossible to produce an incorrect computation even if special efforts are made to do so, or to eliminate any possibility of overspeeding by which a result in the computation might be produced similar to that produced in excessively rapid writing, when one letter is written partly over another because the carriage has not completed its movement before the next printing takes place.

The second safety control is effected by the following mechanism. The plate 253 is extended and bent at right angles to form a lip 255^a, Fig. 29, the lower edge of which lip is adapted to be engaged by a notch 256, formed in a latch 257 pivoted at 258 to a bracket 259 secured upon the plate 61. Said latch is normally pressed toward said lip by means of a spring 260, and is connected by a link 261 with an arm 262 on a rock shaft 263 having suitable bearings on the frame of the machine, (one only shown,) said rock shaft 263 carrying an upwardly extending arm 264, to the upper end of which is connected a link 265 which slides in a guide-way 266, and carries a roller 267. Said roller is adapted to enter the recesses between the teeth of the escapement wheel 268 of the typewriter. When the roller is in one of said recesses, in the normal position of rest, the lip 255^a is beneath a beveled edge 269 of the latch, but, upon the depression of a numeral key and the rocking of the escapement shaft, the upper edge of said lip 255^a engages said beveled edge, and while depressing said latch rises to a position above said notch 256. By the movement of the typewriter escapement wheel 268, which presses outward said roller 267, the latch 257 is withdrawn at the time that the roller 267 is at the extreme point of the tooth on said escapement wheel. The parts are in such position when the numeral key is held down, as shown in Fig. 12. The release of the numeral key simultaneously permits the escapement shaft 83 to rock, which it does under the action of the spring 79, and at the same time allows the roller 267 to pass the point of the typewriter escapement wheel, and thereby allows, the spring 260 to move the latch 256 inward against the lip 255^a of the plate 253. But, on account of the downward movement of said plate 253 simultaneously with the rocking of the escapement shaft, said latch 257 cannot now prevent said downward movement. All of this has been completed before the point of the escapement wheel 89 can pass through the notch in the second disk, so that the carriage has completed its movement before the computing movement begins.

Fourth space lock.—It has already been explained that while, on the depression of a numeral key when the printing point is at each fourth writing space of the typewriter, the numeral will be printed, the computing mechanism will not thereby be effected, because, although the actuating pins are, at the time of such depression, within the third wheel of the group of three computing wheels to the left, yet, upon the release of the numeral key and the consequent movement of the typewriter carriage, said actuating pins move into the open space between the groups of computing wheels in which

they are inoperative; consequently at that point no computation takes place through the rotation of said shaft. However, a common error in writing columns of figures is to write a numeral, out of place, in the space between the groups, or instead of the comma or other character defining the grouping, and were suitable means not provided, the result would be that an operator, having 5 made this error, might continue writing the column without observing the error, receiving the whole computation incorrect, the correction of which would be difficult and complicated. This error would be more especially likely to take place when the typewriter is used with a decimal tabulating mechanism such as in common use with standard typewriters, through an error of the operator in using the wrong tabulating 10 key, such as the tens for the hundreds, or the units for the tens, in which case the figures would occupy the wrong position in the column. It is therefore desirable to provide means for absolutely preventing the 15 depression of a numeral key in such fourth typewriting space, when figures are being printed and the computation is being effected, without interfering with the use of the numeral keys to print the other characters which are printed thereby, even when 20 the computing mechanism is in use.

For this purpose, there are secured upon the rack 191 pins 271 spaced apart four typewriter spaces, and, adapted to engage 25 any one of said pins, is the beveled end of a plate 273 hinged, as shown at 274, to the end of a lever 275. Said plate is maintained in the same plane as said lever when in operative position by means of a hooked 30 latch 276, which, however, can be dropped, whereupon the plate 273 can be swung out of line with the lever 275 and will then not engage said pins 271. The plate 273 is hinged in order that it may be permanently 35 disengaged from the rack 191 in the to and fro movement from the typewriter carriage when not computing. Said lever 275 is suitably pivoted upon the rear of the frame, as shown at 277 and the other end thereof is 40 pivoted to a lever 278, pivoted at 279 upon the frame of the machine, the other end of which is connected to the top of a slide rod 280, which slides through a bracket 281 secured to the plate 2 and normally raised by 45 a spring 282. When said rod 280 is depressed, it is moved into a position in front of the end of the bar 76, which, as already explained is moved to the left by the depression of any numeral key, so that, in the 50 depressed position of the slide rod 280, the bar 76 is locked against such movement, and therefore also every numeral key is also locked thereby. Since the rack 191 moves to the left with the typewriter carriage, each 55 time that the printing point is at each fourth

writing space of the typewriter one of the corresponding pins 271 engages the plate 273 on the end of the lever and depresses the same, thereby depressing the rod 280, and thus locking the numeral keys against depression. 70

However, this construction will not prevent the writing of any other character except the numeral, or the writing of the alternate character carried by the numeral key, 75 as these are written by means of the shift key, and when using the shift key, the connections from the keys, to the computing mechanism are thrown out of operation. In case it is desirable to write a figure in 80 any fourth space without permanently disconnecting the key in each fourth writing space, the depression of the temporary reverse key would have the same effect.

Computing mechanism movement.—Although means have been shown for disconnecting the computing mechanism from the numeral keys, yet this would not prevent the computing mechanism reciprocating with the typewriter carriage, which would be a 90 useless movement. In order to avoid the latter result, there is provided a lever 286 pivoted at 287 on the yoke 288 which is at present provided for the Remington decimal tabulator. Through said lever 286 passes 95 the shaft 193, so that, by rocking said lever, said shaft 193 and the gear wheel 192 can be shifted so that the teeth of the latter are out of mesh with the rack 191. A pin 289 upon the yoke 288 entering in a slot 290 on the lever 286 limits the movement of the lever, which is operated by a knob or handle 291. When the lever has been shifted, so that the gear wheel 192 no longer engages 100 the rack 191, then the carriage 199 of the operating mechanism and the tabulator bar 105 no longer move with the typewriter carriage.

When it is desired to again connect the mechanism, the typewriter carriage is moved to the extreme right and the carriage 199 is moved to the extreme left, and then a fork 292 carried by a spring 293 is caused to straddle the end plate of the carriage 199 for the purpose of centering or justifying the same, so as to insure that, 110 when the lever 286 is again moved, to cause the gear 193 to engage the rack 191, the teeth thereof will properly mesh with each other. The spring is then released, whereupon the fork 292 is disengaged from the end plate of the carriage 199 so that the carriage is properly centered and can travel 115 freely with the movement of the typewriter carriage.

Certain features disclosed herein are contained in earlier applications, No. 388,766 and No. 428,020, involved in interferences, but the claims in this case are limited to features of improvement not disclosed in either of said generic applications. The principal 120 125 130

features of 428,020 (which is in the nature of an improvement on 388,766) may be found in British Patent 8740 of 1909 and French Patent 402,201.

5 I claim:—

1. In a computing attachment for typewriters, the combination of a typewriter carriage, computing mechanism, an actuator therefor, means for intermittently moving one of said latter elements relatively to the other with the movement of the typewriter carriage, means whereby said movable element is automatically advanced relatively to the other element to the extreme end of its relative movement simultaneously with the end of the return movement of the typewriter carriage, means for automatically releasing said element on arriving at said end to permit its return, and means for automatically returning said element when so released, substantially as described.
2. In a computing attachment for typewriters, the combination of a typewriter carriage, computing mechanism, an actuator therefor, means for intermittently moving one of said latter elements relatively to the other with the movement of the typewriter carriage, means whereby said movable element is automatically advanced relatively to the other element to the extreme end of its relative movement simultaneously with the end of the return movement of the typewriter carriage, for the purpose of commencing a new line of writing, means for automatically releasing said element on arriving at said end to permit its return, means for automatically returning said element when so released, and means for variably arresting said element on its return, substantially as described.
3. In a computing attachment for typewriters, the combination of a typewriter carriage, computing mechanism, an actuator therefor, means for intermittently moving one of said latter elements relatively to the other, with the movement of the typewriter carriage, means whereby said movable element is automatically advanced relatively to the other element to the extreme end of its relative movement simultaneously with the end of the return movement of the typewriter carriage for the purpose of commencing a new line of writing, said means being variably located to correspond with the marginal spacing of said commencement, means for automatically releasing said element on arriving at said end to permit its return, and means for automatically returning said element when so released, and means for variably arresting said element on its return, substantially as described.
4. In a computing attachment for typewriters, the combination of a typewriter carriage, a column stop bar, means for moving

said stop bar with the typewriter carriage⁶⁵ but in the opposite direction, computing mechanism, an actuator therefor, means for intermittently moving one of said latter elements with the movement of the column stop bar, a stop adjustably secured upon said column stop bar, and means, arranged to be actuated by said stop, for advancing one of said elements relatively to the other to the extreme end of its relative movement simultaneously with the end of the movement of⁷⁰ the stop bar after said stop has so engaged said means, substantially as described.

5. In a computing attachment for typewriters, the combination of a typewriter carriage, a computing mechanism, an actuator⁸⁰ therefor, means for causing one of said latter elements to move with the typewriter carriage, comprising a rack movable with the typewriter carriage, a gear wheel, and an operative connection between said gear wheel and said element, and means for disengaging at will said gear wheel from said rack to break the operative connection between the typewriter carriage and said element, substantially as described.⁸⁵

6. In a computing attachment for typewriters, the combination of a typewriter carriage, a computing mechanism, an actuator therefor, means for causing one of said latter elements to move with the typewriter carriage, comprising a rack movable with the typewriter carriage, a gear wheel, and an operative connection between said gear wheel and said element, means, for disengaging at will said gear wheel from said⁹⁰ rack to break the operative connection between the typewriter carriage and said element, and means for centering said element relatively to the typewriter carriage before again connecting the said gear wheel and⁹⁵ rack, substantially as described.

7. In a computing attachment for typewriters, the combination of a typewriter carriage, computing mechanism, an actuator therefor, means for operatively connecting one of said elements with the typewriter carriage to cause it to move in unison therewith, means for breaking said connection at will, and for connecting again when desired, and means for justifying said element relatively to the typewriter carriage before again making such connection, substantially as described.¹¹⁰

8. In a computing attachment for typewriters, the combination of a typewriter carriage, computing mechanism, an actuator therefor, means for moving one of said elements with the typewriter carriage, numeral keys, means for controlling the operation of said actuator by the depression of a numeral key, means interposed between said numeral keys and actuator for preventing the depression of a numeral key, car-

- riage tappets arranged at each fourth writing space of the typewriter, and a key-locking cam mechanism operable by said tappets.
9. In a computing attachment for typewriters, the combination of a typewriter carriage, computing mechanism, an actuator therefor, means for moving one of said elements with the typewriter carriage, numeral keys, means for printing by the depression of the numeral keys and means controlled by said carriage for operating said actuator after the printing has been effected through the depression of a numeral key and after the typewriter carriage has moved into position ready for the next printing operation.
10. In a computing attachment for typewriters, the combination of a typewriter carriage, numeral keys, computing mechanism, an actuator therefor, means for rotating said actuator, means dependent upon the depression of a numeral key for variably limiting the extent of said rotation, and means controlled by said carriage for producing a movement of one of said elements, the actuator and computing mechanism, relative to the other, said carriage preventing rotation of said computing mechanism until said relative movement is completed.
11. In a computing machine, the combination of computing mechanism including denominational members and a master means, relatively movable to enable the master means to drive the denominational members *seriatim*, of keys for controlling the amount of turning of said master means on depression of said keys and controlling means for preventing the turning of said master means after a key has been depressed and until said master means is in engagement with the proper denominational member.
12. In a computing attachment for typewriters, the combination of a typewriter carriage, a rack movable therewith having a series of pins, one corresponding to each fourth writing space of the typewriter, a lever successively operated by said pins, computing mechanism, numeral keys therefor, and means operated by said lever when so actuated for rendering said computing mechanism inoperative, substantially as described.
13. In a computing attachment for typewriters, the combination of a typewriter carriage, a rack movable therewith having a series of pins, one corresponding to each fourth writing space of the typewriter, a lever successively operated by said pins, computing mechanism, numeral keys therefor, and means operated by said lever when so actuated for preventing the depression of the numeral keys, substantially as described.
14. In a computing attachment for typewriters, the combination of a typewriter carriage, a rack movable therewith having a series of pins, one corresponding to each fourth writing space of the typewriter, a lever successively operated by said pins, computing mechanism, numeral keys therefor, and means operated by said lever when so actuated for rendering said computing mechanism inoperative, substantially as described.
15. In a computing attachment for typewriters, the combination of a typewriter carriage, computing mechanism comprising computing devices spaced into groups of three, an actuator therefor, means for moving one of said elements with the typewriter carriage, numeral keys, a device adapted to be actuated by the depression of any one of said numeral keys to cause said actuator to operate, and means for preventing the actuation of said key-actuated device at any punctuation point, including a series of carriage tappets and a cam mechanism successively operable thereby and extending to position to prevent the operation of said keys.
16. The combination with a carriage, of an escapement mechanism for said carriage, a computing mechanism, an escapement mechanism for said computing mechanism and means for controlling the escapement mechanism of said computing mechanism from the escapement mechanism of said carriage.
17. The combination with a computing mechanism, of a typewriting mechanism having numeral keys, connections for subjecting the action of said computing mechanism to said numeral keys, yielding means for disconnecting said connections to leave said keys free from said computing mechanism, and means for temporarily overcoming said yielding means and to complete the connection, to bring said computing mechanism under the control of said numeral keys.
18. The combination with a computing mechanism, of a typewriting mechanism having numeral keys, connections for subjecting the action of said computing mechanism to said numeral keys, yielding means capable of moving said connections to effective positions, and means for temporarily overcoming said yielding means to momentarily interrupt the connection, to leave said keys free from the drag of said computing mechanism.
19. The combination with a computing mechanism, of a typewriting mechanism having numeral keys, connections for subjecting the action of said computing mechanism to said numeral keys, controlling means settable for permanently determining

- the effectiveness of said connections, and temporarily acting manually operable means for momentarily overcoming said controlling means to reverse the action without altering the setting thereof, whereby said connections will be temporarily interrupted if permanently effective, and temporarily completed if permanently ineffective. 5
- 10 20. The combination with a computing mechanism, of a typewriting mechanism, connections for synchronizing the action of said mechanisms, settable means to make said connections normally effective or ineffective, and spring means yielding in either position of said settable means, to enable the temporary reversal of either the effectiveness or the ineffectiveness of said connections, without interfering with the normal 15 set of said settable means. 20
21. The combination with a typewriting mechanism, of a computing mechanism, connections enabling the concomitant action of said typewriting mechanism and said computing mechanism, means capable of being set to make said connections normally effective or ineffective, and means for temporarily reversing either state of said connections while leaving the said second means 25 where originally set. 30
22. The combination with a typewriting mechanism having numeral keys and a carriage, of a computing mechanism, connections for subjecting the action of said computing mechanism to the action of said numeral keys, and permanent and temporary means each manually movable and each capable of determining the effectiveness or ineffectiveness of said connections. 35
- 40 23. The combination with a carriage having a step-by-step movement, of a power-driven computing mechanism comprising an escapement, keys for setting said escapement and controlling said carriage, and means for delaying the individual computing action of the escapement of said mechanism after it is set, until said carriage has completed each movement. 45
24. In a combined typewriting and computing machine, the combination with a traveling carriage, a gang of computing wheels and a master wheel for turning them *scriatim*, of a device for connecting said carriage to cause relative movement between 50 said master wheel and said computing wheels, means for normally moving said master wheel to engage with the computing wheel of highest denomination, and means for causing the return of said carriage to the 55 beginning of a new line to positively cause said master wheel to engage a computing wheel of a lower denomination. 60
25. In a combined typewriting and computing machine, the combination with a traveling carriage, a gang of computing 65
- wheels and a master wheel for turning them *scriatim*, of a device for intermittently connecting said carriage to cause relative movement between said master wheel and said computing wheels, means for normally moving said master wheel to engage with a computing wheel of high denomination, and a stop connected to said traveling carriage settable to cause said master wheel to engage a computing wheel of a lower denomination. 70 75
26. In a combined typewriting and computing machine, the combination with numeral keys and a traveling carriage, of computing wheels, a device settable by said keys for determining how far any computing wheel shall be turned, a step-by-step feeding device for said carriage controlled by said keys, and means controlled by the movement of said carriage as it is fed by a numeral key, and after said numeral key has set said device, for turning the computing wheel by said device. 80 85
27. In a combined typewriting and computing machine, the combination with numeral keys and computing wheels, of a power-driven device, an escapement for said device, means controlled by the numeral keys for setting said escapement to determine how far said power shall turn any wheel, a letter-feeding escapement for said carriage controlled by said keys, a latch holding said computing escapement, and means operated by the completion of the letter-feeding of said carriage for releasing said latch to permit said escapement to feed. 90 95 100
28. In a combined typewriting and computing machine, the combination with a traveling carriage, of computing wheels, means controlled by said traveling carriage for determining when said wheels shall turn, and separate means on said traveling carriage for preventing the turning of said wheels at certain predetermined points in the travel of said carriage. 105
29. The combination with a carriage, of a computing mechanism, connections between said carriage and said computing mechanism, whereby said carriage may control the movement of said computing mechanism during letter-spacing movements of said carriage, and other connections between said carriage and said computing mechanism, whereby said carriage may control the movement of said computing mechanism during its return movement. 110 115 120
30. In a combined typewriting and computing machine, the combination with a carriage, of a computing mechanism for computing a plurality of denominational columns of numbers, a computing mechanism for cross-computing said columns, and means for so adjusting said computing mechanism and said cross-computing mechanism that a column or columns of numbers printed at any portion of the line of writing may be 125 130

computed in any column of said computing mechanism and simultaneously in any column of the cross-computing mechanism.

31. The combination with a computing mechanism capable of computing a plurality of columns of numbers, of a totalizer capable of computing all of the numbers in all of the columns to obtain a grand total, said computing mechanism and said totalizer normally adjusted to compute in corresponding denominational columns, and means for effecting an abnormal adjustment of the denominational relation between said totalizer and said computing mechanism in respect to the initial column before computing each number in said initial column.

32. The combination with a long totalizer, of a supplementary short totalizer, means for repeatedly bringing said short totalizer in register with several sections of said long totalizer, and means to enable said last-mentioned means to bring any computing wheel of said supplementary totalizer in register with the initial wheel of said long totalizer.

33. In a combined typewriting and computing machine, the combination with a traveling typewriter carriage, of a computing carriage, numeral keys, a comma lock for said keys operated by the typewriter carriage, and means settable to cause said carriages to travel step by step together, said means settable only at such points as will cause the comma lock to become effective at the proper time.

34. In a computing machine, the combination with computing wheels and numeral keys, of a universal member actuated by said keys for controlling the turning of said wheels, a traveling carriage, a comma lock effective on said universal member for preventing actuation of a numeral key at an improper position in the travel of said carriage, a case shift, and means for disconnecting said keys from said universal member when said case is shifted to thereby render said comma lock ineffective.

35. In a computing machine, the combination with computing wheels and numeral keys, of a universal member actuated by said keys for controlling the turning of said wheels, a traveling carriage, a comma lock effective on said universal member for preventing actuation of a numeral key at an improper position in the travel of said carriage, a case shift, means for disconnecting said keys from said universal member when said case is shifted, to thereby render said comma lock ineffective, and independent means for making said comma lock ineffective.

36. In a combined typewriting and computing machine, the combination with numeral keys and computing devices, of connections, extending from said keys to said

computing devices, a comma lock, connections whereby when said keys are connected to said computing devices they are connected to said comma lock, and when disconnected from said devices are disconnected from said comma lock, and means independent of said connection for making said comma lock ineffective.

37. In a computing machine, the combination with a totalizer divided so as to be capable of use as a series of footing totalizers including an initial narrow one, of a master wheel for said totalizers, a traveling carriage controlling the relation of said totalizers and master wheel, a cross totalizer of greater length than said initial totalizer, a master wheel for said cross totalizer, a cross computing carriage for said cross totalizer intermittently connectible to said traveling carriage, and means for automatically adjusting the relation of the series totalizer and the cross totalizer so as to add in the correct denomination of said cross totalizer at the operation of computing in the initial totalizer.

38. In a combined typewriting and computing machine, the combination with a letter-feeding typewriter carriage, of a main computing mechanism including an element connected to the typewriter carriage to travel therewith in the opposite direction therefrom, a cross-computing mechanism including an element connected to travel with said typewriter carriage and return intermittently during each run of the typewriter carriage, and manually operable means for simultaneously disconnecting both said main traveling element and said cross-computing traveling element from said typewriter carriage.

39. In a combined typewriting and computing machine, the combination with a letter-feeding typewriter carriage, of a main computing mechanism including an element connected to the typewriter carriage to travel therewith, a cross-computing mechanism including an element connected to said main traveling element to travel therewith intermittently during each run of the typewriter carriage, manually operable means for disconnecting said cross-computing element from said main computing element, and separate manually operable means for disconnecting both said main traveling element and said cross-computing element from said typewriter carriage.

40. In a combined typewriting and computing machine, the combination with typewriter numeral keys and a case-shift mechanism, of computing mechanism, connecting means between the computing mechanism and the keys, settable means for permanently effecting either connection or disconnection between the keys and the computing mechanism, temporary means for reversing the

- condition to which said connections are permanently set, and means connected to said case-shift mechanism and acting on said connections for effecting disconnection between the keys and the computing mechanism when the case-shift mechanism is shifted to abnormal position.
41. In a computing attachment for typewriters, the combination of numeral keys, a computing mechanism, individual means for connecting said numeral keys with said computing mechanism, a device for connecting said individual means with said numeral keys, a double-acting spring, a key arranged to move said device and also to move said spring from one position of equilibrium to another, whereby, on the depression of said key, said individual means are stably connected with the numeral keys, and a second key arranged to make such connection, but inoperative to shift the position of said spring, whereby, upon the depression of said second key, the connection is unstably made.
42. In a computing attachment for typewriters, the combination of numeral keys, computing mechanism, individual means for controlling said computing mechanism by said numeral keys, a device for simultaneously connecting all of said individual means with, or disconnecting them from, said numeral keys, two keys for operating said devices to connect, or disconnect, said individual means with, or from, the numeral keys, and a spring arranged to maintain the parts in the position to which they have been moved by the operation of one of said keys, and to restore the parts to their original positions, after they have been moved by the operation of the other key.
43. In a computing attachment for typewriters having double case type and a typewriter shift key, the combination of numeral keys, computing mechanism, individual means for controlling said computing mechanism, a device for simultaneously connecting all of said individual means with corresponding numeral keys and disconnecting them therefrom, means whereby the operation of the shift key operates said device to disconnect said individual means whereby the numeral keys may be actuated for printing other than numerals without affecting the computing mechanism, a spring arranged to return the parts to their original positions and again connect said means with the numeral keys when the shift key is released, and a second key arranged when depressed to disconnect said individual means from the numeral keys so that numerals may be printed while said key is depressed without affecting the computing mechanism, said spring also operating to return the parts to their original positions upon the release of said second key.
44. The combination with a computing mechanism, of a series of numeral keys, connections for operatively joining said computing mechanism to said numeral keys to enable the action of said computing mechanism to be controlled by said numeral keys, said connections being permanently settable to effective and ineffective positions, and a single separate key always capable of temporarily rendering said connections effective or ineffective.
45. In a combined typewriting and computing machine having double case type and a typewriter shift key, the combination of numeral keys, computing mechanism comprising individual means connecting it to each numeral key, a manually operated device for connecting said keys with and disconnecting them from said computing mechanism, means whereby the operation of the shift key operates said device to disconnect said individual means whereby the numeral keys may be actuated for printing other than numerals without affecting the computing mechanism, a spring arranged to return the parts to their original positions and again connect said means with the numeral keys when the shift key is released, and a second key arranged when depressed to disconnect said individual means from the numeral keys so that numerals may be printed while said key is depressed without affecting the computing mechanism, said spring also operating to return the parts to their original positions upon the release of said second key.
46. In a typewriting and computing machine, the combination of a typewriter carriage, computing mechanism, an escapement therefor, and means whereby said escapement is controlled through a movement of the carriage.
47. In a typewriting and computing machine, the combination of a carriage, means for moving said carriage, an escapement therefor, computing mechanism, means for actuating said computing mechanism, and means controlled by the typewriter carriage escapement, for preventing actuation of said computing means to perform computation thereby until the carriage has completed its movement.
48. In a typewriting and computing machine, the combination of a typewriter carriage, an escapement therefor, computing mechanism, a controller therefor, an escapement for said controller, an escapement shaft therefor, and means controlled by the typewriter escapement, for preventing the rocking of said shaft in one position of said escapement.
49. In a typewriting and computing machine, the combination of a carriage, computing mechanism, keys, means controlled by said keys for moving said carriage, means

- rendered effective by the up strokes of said keys for operating said computing mechanism, and means for preventing the operation of said computing mechanism during the movement of the carriage after having been rendered effective by said keys.
50. In a typewriting and computing machine, the combination of a typewriter carriage, an escapement therefor, computing mechanism, a controller therefor, an escapement for said controller, an escapement shaft therefor, and a spring-actuated latch controlled by the typewriter escapement, for preventing the rocking of said shaft in one position of said escapement.
51. In a combined typewriting and computing machine, the combination with keys, a typewriter carriage and an escapement wheel therefor, a power-driven computing device, and means, including an escapement device to enable the keys to control said computing device, of means dependent upon the return strokes of the keys and controlled by said escapement wheel to hold the escapement device of the computing mechanism temporarily against actuation, whereby the movement of the carriage must be completed before the movement of the computing mechanism is completed.
52. In a computing machine, the combination of computing mechanism, numeral keys therefor, means whereby said computing mechanism is controlled by the operation of a numeral key, and means dependent upon the operation of the computing mechanism for preventing the depression of any numeral key until said computing mechanism has completed its movement due to the previous operation of a numeral key, substantially as described.
53. In a typewriting and computing machine, the combination of a typewriter carriage, computing mechanism, numeral keys, said carriage under the control of said keys, means for controlling said computing mechanism through the depression of a numeral key, means for controlling the operation of the computing mechanism by the movement of the carriage, and means for controlling the operation of the numeral keys by the movement of the computing mechanism, substantially as described.
54. In a computing machine, the combination with numeral keys and a traveling carriage, of a universal key-locking member operated by said keys, and an automatic latch therefor, releasable by said carriage.
55. In a computing machine, the combination with a key-locking device effective on several keys, of a computing escapement, a spring tending to hold said locking device effective, and means whereby said escapement normally holds the locking device ineffective.
56. In a computing machine, the combination with a key-locking device effective on several keys, of a computing escapement, a spring normally tending to hold said locking device effective unless positively held ineffective by said escapement, and means whereby said escapement is ineffective on said spring during the interval computing is actually being done.
57. The combination with a computing mechanism, of a series of numeral keys, means settable by said keys on their down-strokes to determine the amount of movement of said computing mechanism, means brought into action during the return stroke of any key for moving said computing mechanism under control of said key, and means for preventing the same key or any other key from acting on said settable means to determine a second computing operation, during the movement of the computing mechanism under the control of the first key.
58. The combination with a computing mechanism, of numeral keys, means settable by said keys for determining how far said computing mechanism shall move, a universal member operated by any of said keys, and means brought into action on movement of the computing mechanism under the control of any key for locking said universal member against movement, to thereby prevent the movement of the same key or any other key until the computing mechanism has completed its operation, the completion of the operation of said computing mechanism releasing said lock.
59. The combination with a computing mechanism, of a series of keys, valuating mechanism controlled by said keys to determine how far said computing mechanism shall move, and means controlled by said valuating mechanism to prevent the same key or any other key from determining how far said computing mechanism shall move while said mechanism is moving under the control of the first key.
60. The combination of a power-driven computing mechanism having an escapement wheel, a carriage, said computing mechanism including a member connected to move step by step at the feeding movement of the carriage, normally ineffective means extending from said carriage to said escapement wheel to enable the movement of the carriage to release said escapement wheel, a set of numeral keys, carriage-feeding devices controlled by said keys, means controllable by any of said keys to render effective at the letter-feeding movement of the carriage the devices which extend from said carriage to said escapement wheel, whereby the escapement wheel is released, and mechanism extending from said keys to said escapement wheel to determine the extent of movement of the latter.

61. The combination of a step-by-step feeding-carriage, keys to operate said carriage, a rack-and-pallet mechanism connected to said carriage, a computing mechanism including a member connected to said carriage for a denominational step-by-step movement, means controlled by said rack-and-pallet mechanism to start and stop said computing mechanism, and means controlled by said keys to determine the extent of operation of said computing mechanism.

62. The combination of a step-by-step feeding-carriage, a set of numeral keys having means to control said carriage, a power-driven computing mechanism including a member connected to said carriage for a denominational movement and also including an escapement wheel, a dog device to control said escapement wheel, a normally ineffective interponent for rendering the movement of said dog device subject to the movement of said carriage, means controlled by said keys to render the operation of said dog device subject to the controlling effect of said carriage-controlled interponent, and means controlled by said keys to determine the extent of movement of said escapement wheel.

63. The combination of a computing mechanism including a power-driven escapement wheel provided with settable escapement teeth, keys having means to set said teeth, a feeding dog normally restraining said escapement wheel, a step-by-step feeding-carriage controlled by said keys, said computing mechanism including a member connected to said carriage to have a denominational movement, and means controlled by said carriage to operate said feeding dog to release said escapement wheel during the concluding portion of the letter-feeding movement of the carriage.

64. The combination of a letter-feeding carriage, a computing mechanism having an escapement wheel and including a member connected to have a denominational movement at the letter-feeding movement of the carriage, normally ineffective means extending from said carriage to said escapement wheel, to enable the carriage to control said escapement wheel, a set of type-operating numeral keys, carriage feeding devices controlled by said keys, disconnectible means connected to said keys and extending therefrom to said escapement wheel, to determine the extent of movement of the latter, and disconnectible means also connected to said keys to render effective, at the letter-feeding movement of the carriage, said devices which extend from said carriage to said escapement wheel to control the latter.

65. The combination of a letter-feeding carriage, a power-driven computing mechanism having an escapement wheel and including a member connected to have a denominational movement at the letter-feed-

ing movement of the carriage, normally ineffective means extending from said carriage to said escapement wheel, to enable the carriage to release said escapement wheel, a set of type-operating numeral keys, carriage-feeding devices controlled by said keys, connections extending from said keys to said escapement wheel to determine the extent of movement of the latter, means for breaking said connections, a universal bar or disk operated by said connections, and means controlled by said universal bar or disk to render effective, at the letter-feeding movement of the carriage, the devices which extend from said carriage to said escapement wheel to release the latter.

66. The combination with a letter-feeding carriage having a rack, of a computing mechanism having an escapement wheel, a dog, and a pallet subject to the operation of said rack and controlling the operation of said dog in such a manner that the escapement wheel of the adding mechanism is released by said dog at the concluding portion of the letter-feeding movement of the carriage.

67. The combination with a typewriter, including a traveling carriage and an escapement therefor, of a computing mechanism, a source of power, means for driving said computing mechanism from said source of power, an escapement for said source of power, and key-operated means for setting said last-named escapement and starting said first-named escapement to operate the last-named escapement.

68. In a combined typewriting and computing machine, the combination with type-operating keys, of a traveling carriage controlled by said keys, a rack moving with every movement of said carriage, a computing mechanism comprising a series of computing wheels and a common escapement wheel, the extent of rotation of the computing wheels being controlled by said keys, means for driving said computing mechanism, a dog restraining the operation of said escapement wheel, and a controller comprising a member movable by said rack to free said escapement wheel from said dog by the movement of the carriage.

69. The combination with a typewriter carriage, and letter-feeding devices therefor, of a computing mechanism including parts directly actuated by said letter-feeding devices for timing the operation of the computing mechanism relative to the movement of the carriage.

70. The combination of a typewriter carriage, numeral keys which control said carriage, a computing mechanism including indexing devices under the control of said keys, whereby the depression of a key determines the extent of operation of the computing mechanism, and computing mecha-

nism operating means called into action through the key-controlled carriage-controlling devices, for completing the computing operation preparatory to the setting of the indexing devices for the next computation.

71. In a computing machine, the combination with computing mechanism of a master member, a step-by-step feeding carriage, means controlled from said carriage for moving said computing mechanism and master member relatively to one another from higher to lower orders during the step-

by-step feeding movement of said carriage and means for moving said computing mechanism and master member relatively 15 to one another from higher to lower orders on the return movement of said carriage.

In testimony whereof I have hereunto set my hand in the presence of two subscribing witnesses.

WALTER WRIGHT.
